CERTIFICATE OF CORRECTION

PATENT NO. : Des. 609,999 S
APPLICATION NO. : 29/323462
DATED : February 16, 2010
INVENTOR(S) : Mattias Andersson

Page 1 of 4

It is certified that error appears in the above-identified patent and that said Letters Patent is hereby corrected as shown below:

Delete title page showing an illustrative figure and substitute the attached title page therefor.

Delete drawing sheets 1 and 2, substitute the attached drawing sheets 1 and 2 therefor.

Signed and Sealed this

Sixth Day of July, 2010

David J. Kappos
Director of the United States Patent and Trademark Office
